Patented Sept. 5, 1922.

FIG. 1.

FIG. 2.

FIG. 3.

Inventor
J.M. Ronalter

Attorney
A. Hauberg, Jr.

UNITED STATES PATENT OFFICE.

JOSEPH M. RONALTER, OF STAFFORD SPRINGS, CONNECTICUT.

ELECTRIC SWITCH.

Application filed October 7, 1920. Serial No. 415,282.

To all whom it may concern:

Be it known that I, JOSEPH M. RONALTER, a citizen of the United States, residing at Stafford Springs, in the county of Tolland 5 and State of Connecticut, have invented certain new and useful Improvements in Electric Switches; and I do hereby declare the following to be a full, clear, and exact description of the invention, such as will enable 10 others skilled in the art to which it appertains to make and use the same.

The object of the invention is to provide a simple and comparatively inexpensive apparatus which may be used in connection 15 with a timing device such as an alarm clock or the equivalent thereof and may be introduced into or included in a lighting circuit such as used for stores, buildings, display signs and the like to effect the closing or the 20 opening of the circuit at a predetermined time in advance without requiring the attention at the moment of the operator or attendant; and more especially to provide an 25 apparatus for the purpose indicated in which an ordinary alarm clock may be positioned when it is desired to time the switch for operation automatically, the clock or 30 time piece under ordinary conditions being used for its normal purpose; and with these 35 objects in view the invention consists in a construction and combination of parts of which a preferred embodiment is shown in the accompanying drawings wherein;

Figure 1 is a side view of the device showing an alarm clock arranged in operative relation therewith.

Figure 2 is a front view.

Figure 3 is a detail view of the clutch bit for engaging the alarm key.

40 Mounted upon a suitable base 10 having a seat 11 for an alarm clock 12 of the ordinary commercial type is a standard 13 carrying a revoluble switch spindle 14 to the front end of which is attached a setting knob 15 and to the rear end of which is fixed a clutch 45 disc 16 perforated as shown at 17 for engagement with the prongs of an ordinary alarm clock key 18. A coiled spring 19 may be arranged upon the spindle to hold the 50 clutch disc in engagement with the prongs of the alarm key and also to maintain a proper yielding contact of the switch tongue 20 in position for engagement with a terminal 21 shown in the drawing as of arcuate 55 form, said switch tongue and terminal 21

being connected by circuit wires 22 and 23 with the binding posts 24 with which connection may be made to a lighting circuit.

Arranged in the path of movement of the switch tongue are the stops 25 and 26 serving to check the rotary movement of said tongue in either direction, and respectively in contact with the terminal 21 and out of contact therewith, according to whether the switch at a predetermined time set by the 60 alarm clock is to be either opened or closed. The alarm clock obviously may be set in the ordinary way to be released at a predetermined time, and when the alarm is released the key 18 is rotated and communicates motion through the clutch disc to the spindle of the switch which causes the switch tongue either to come into contact with or to move out of contact with the terminal 21 until checked by one or the other of the stop pins 65 25 and 26. The clutch disc is screw threaded on the spindle 14 so as to turn. Obviously if the switch is to remain closed, to correspondingly maintain the lighting circuit 70 closed until a predetermined time at which 75 it is desired that it shall be opened, the switch tongue should be arranged in the position indicated in full lines in Figure 2 substantially in contact with the stop pin 25 and in contact with the terminal 21, and 80 when the alarm is released said switch tongue will be turned to the dotted line position as in Figure 2. On the other hand if the desire of the operator is to leave the 85 circuit open and have it closed at a predetermined time in advance the switch should be pulled against the tension of spring 19 and moved across contact 26 so that when 90 the alarm sounds the switch tongue will be turned until it comes into contact with the 95 stop pin 25 and therefore in engagement with the terminal 21, whereupon further movement of the switch tongue will be prevented, the clutch disc turning idly upon the switch spindle.

100

What is claimed is:—

1. An electric switch apparatus including a switch device having a clutch, and an alarm clock, means to urge the clutch into engagement with the spindle of said alarm 105 clock, and means to mount the clock against displacement under urgency of said first mentioned means.

2. An electric switch apparatus having a standard, a spindle journaled and slidably 110

mounted therein, a switch arm on said spindle, means engageable by the arm to enclose an electric circuit, stop means engageable by said arm, and an attaching clutch on the 5 spindle, and a spring to urge said clutch away from the standards and to permit retraction of the spindle to facilitate movement of the switch arm across the stop means.

- 10 3. An electrical switch apparatus having a base provided with a seat for an alarm clock, a revoluble spindle mounted upon a standard of said base, a switch tongue carried by the spindle, an arcuate terminal arranged in the path of movement of said 15 switch tongue, the switch tongue and ter-

20 minal being electrically connected with binding posts, stops for limiting the movement of the switch tongue, a perforated clutch disc mounted upon the spindle for engagement with an alarm clock key, and a spring coiled upon the spindle in terminal engagement with said clutch disc for yieldingly holding the latter in turning relation with the spindle. 25

In testimony whereof I affix my signature in presence of two witnesses.

JOSEPH M. RONALTER.
